VALVE MECHANISM

Warren Noble, Michigan City, Ind., assignor to
 Sullivan Machinery Company, a corporation of
 Massachusetts

Application June 1, 1935, Serial No. 24,569

5 Claims. (Cl. 251—119)

This invention relates to valve mechanisms, and more particularly to improvements in valve springs for use with annular disc valves of the type commonly used for automatically controlling intake and discharge of fluid with respect to the cylinders of air compressors or pumps.

Valves of the flat ring type are well known, and comprise a flat annulus, which may be either flexible or rigid, guided axially and limited as to lift by suitable overhanging structure, the lift of the valve being opposed by one or more springs which may be helical, spiral or ring-like in form. Hitherto, valve springs of the ring type have been made from flat steel, formed first as a plane washer and later bent to arcuate form so that the tips of the arc, or lips at the ends of the arc, abut the surface of the valve, and the center of the arc abuts the "guard" or stop structure which limits the lift. The advantages of this form of valve spring are sufficient to make its use very general. It occupies a minimum of space, is simply made, and may be laminated for any desired strength and to make for reliability. It suffers the disability that in it a portion of its bulk is utilized as active material and the inevitable unequal distribution of stress tends to some unreliability, though in general it is very satisfactory. At the expense of simplicity of fabrication, the durability and action of such springs may be improved by making either the inside or outside of the spring washer elliptical and bending the latter suitably with respect to the axes of the ellipse to provide the valve and stop abutments, but at the best the stress distribution is imperfect, and remains unfavorable to great continuity of service. It is well known to those skilled in the art that the reliability of such springs is materially affected by the degree of surface polish, and especially by the perfection of finish on the edges. By concentration upon mechanical perfection, vast improvement has been made. The unequal distribution of stress in the material, however, remains as a deteriorating influence, casting the shadow of uncertainty on spring life.

This invention has for one of its objects the provision of an improved valve-spring, and a primary aspect thereof involves the substitution for the rectangular-section, ring-type spring, of one of circular cross section, similarly bent into arcuate form for contacting with the valve and stop surfaces, and located by any suitable means between the valve and stop surfaces. As the spring quality invoked has its being through torsional stress in the section; and as this cannot exist unequally within the confines of a toroid, all the material involved in a spring of the im-

proved type mentioned is unequally stressed, a condition enabling a sufficiency of spring action to be obtained with lower fibre stress in the material from which the spring is made. For any desired strength of spring the minimum possible fibre stress is thus automatically achieved. As the form is such as to be especially easy to fabricate free of surface defects, an approach to complete reliability has been opened and the space and weight characteristics of the spring both improved. Further objects of the invention are to provide an improved valve element and an improved guard element with which the improved spring may coact, and a still further object is to provide an improved valve mechanism comprising the improved spring and valve elements herein described in illustrative forms. Other objects and advantages of the invention will hereinafter more fully appear in the course of the following description and as more particularly pointed out in the appended claims.

In the accompanying drawing there is shown for purposes of illustration one form which the invention may assume in practice.

In this drawing,

Fig. 1 is a central section through a compressor or pump valve mechanism embodying the illustrative form of the invention.

Fig. 2 is a perspective view of the improved valve spring.

Fig. 3 is a plan view of the valve stop or guard.

Fig. 4 is a cross sectional view taken on line 4—4 of Fig. 3.

Fig. 5 is a plan view of a valve.

Fig. 6 is a cross sectional view taken on line 6—6 of Fig. 5.

Fig. 7 is an elevational view of the improved valve spring.

In this illustrative embodiment of the invention the improved valve mechanism is shown associated with a compressor or pump cylinder member shown at 1 having a liner 2 and a co-operating head member 3. Within the head member a chamber 4 is formed which is divided into different portions by valve cage elements later described. One of these portions communicates through an opening 5 with the bore of the cylinder, while another portion communicates through a passage 6 with the discharge space of the compressor cylinder.

The valve mechanism comprises a pair of cage or seat elements 7 and 8, the element 7 being the inlet valve seat element and the element 8, the discharge valve seat element. These valve seat elements are held in position by a stud 9 threaded at 10 within the cylinder 1, and having 55

associated therewith nuts 11 and 12 which serve respectively to hold the cage elements 7 and 8 in position. Each of the cage elements is held in tight sealing engagement with a shoulder formed in the head element 3, as by gaskets sealing the joints between the cage elements and the shoulders on the head element. The portions of the head element 3 which provides the shoulders are respectively designated 13, in the case of the inlet cage element, and 14 in the case of the discharge cage element. The inlet valve seat or cage element 7 has a valve seat 15 formed thereon surrounding a port 16. An improved valve 17, of comparatively thin, flexible metal, is associated with the seat 15 and normally held in closed position by a transversely bowed annular spring 18 of an improved form. The spring 18 and valve 17 are guided during movement by guiding wings 19 formed integral with the valve seat element 7. Similarly, the discharge seat or cage element is provided with an annular port 20, surrounded by a valve seat 21, with which an improved annular valve 22 cooperates. The valve 22 is yieldingly seated by a valve spring 23 likewise of improved form, guided by guiding wings 24 formed integral with the valve seat element 8. Mounted in spaced relation to each of the valves mentioned above is an improved valve guard composed of sheet metal of comparatively thin resilient material, the guard for the valve 17 being indicated by the numeral 25 and the guard for the valve 22 by the numeral 26. These guards 25 and 26 are secured to the guiding wings 19 and 24 of the valve seat elements 7 and 8 by screws 27.

As previously mentioned, the valve springs 18 and 23 are of improved form, each having a circular cross section. Such a valve spring, having been, prior to arcuate formation, a circular ring, may, in compressed condition, be completely located within a circular groove or recess, which recess it will only partially fill in its unloaded (flexed) position. The difference in distance between the chordal tips of the spring unloaded (i. e. bent) and the diameter of the circular form from which the spring is bent, is actually very small, so that the slight incompleteness of guiding thus occasioned is not detrimental to the valve action. The slight float between the seating surfaces on the valve proper and the cooperative seat surfaces of the valve cage element is definitely beneficial and does much to prolong the life of both seat and valve.

The ring of spring wire which constitutes the improved spring appears at first sight to be a simple form, easy to manufacture. There are, however, certain metallurgical difficulties in the way of making a perfect ring of uniform metallic structure, notably due to the disinclination of the higher carbon steels, (such as are used for spring-making) to weld successfully. The forming of a ring and welding its ends as at 28 in Fig. 7 to make it continuous is therefore subject to the danger that the carbon content of the steel will be burned out during the welding and the section of the ring including the weld therefore have poorer physical characteristics than the remainder of the circle. Provided the spring is not too highly stressed and the welding flash and adjacent surfaces properly cleaned and polished, the dissimilarity of metallic structure engendered is not very important, but if in the search for lightness and economy of space (subscribing to better characteristics for the compressor or pump) the steel of the ring is stressed

well up in its elastic range, danger exists that the yield point of the resultant metal in weld-deteriorated section may be approached. In order to avoid this, such springs are better made from steel wire or low carbon content, formed, welded 5 into a continuous ring, bent to arcuate contour and then carburized by being heated in a carburizing box or in a hot retort in an atmosphere of gas rich in carbon, the latter being perhaps the more desirable method for this particular 10 article. Subsequent to the permeation of the surface of the ring with the additional carbon (to any desired depth, or if necessary completely through the section) it is finally polished, reheated in a neutral atmosphere, quenched and 15 drawn. A homogeneous metallic structure, without danger of weakness in the weld zone, is thus achieved.

There are other practical ways of making such springs. High carbon wire may be welded in a 20 nitrogen atmosphere without marked deterioration at the weld. Again, it is known that hydrogen brazing satisfactorily joins the adjacent ends of ring hoops. In this case, however, despite the penetration of the steel structure by 25 the copper, the joint remains as a section of the brazing metal inferior in physical characteristics to the steel. Obviously rings may be cut off a high carbon steel tube in a turning machine by the use of suitable forming tools, polished on 30 separate machines and hardened in the ordinary course of events. Danger of occlusions in the original tube wall casts shadow upon the probable reliability of springs so made. In order to avoid some of this trouble a small ring expanded 35 in rolls to provide planishing of the surface and partial elimination of any direct transverse occlusion strand may be used.

The forming of the ring from low carbon steel wire, welding the hoop, eliminating the mechanical traces of the weld, bending to arcuate form, carburizing in a gas atmosphere with the spring continuously moving, repolishing, reheating in a neutral atmosphere, quenching, drawing, and again repolishing before final rust protection plating is in sequence probably the best method 45 of fabricating a completely satisfactory spring of this type.

With automatic intake and discharge valves of the type disclosed the mass of the valve is of 50 importance. If the valve is heavy more energy is used in lifting it and its impact on the stop is more destructive. Lightness has usually been achieved by utilizing a thin, hence flexible valve washer or annulus. Here the valve itself becomes part of the spring system and by reason of its 55 form suffers the disabilities which the circular section ring spring avoid. In constructing for superior reliability, therefore, it is necessary to take away from the valve element any self springing action and substitute the ability for self-location in order that the dual function of springing and guiding may be allocated to the single wire ring. However, flexibility on the part of the valve, in a radial direction, is beneficial, so that 60 the valves 17 and 22 are made by adding a relatively deep annular groove or channel 29 (as distinct from a bead) midway between the outer and inner peripheries of the valve ring. With this provision the valve can be formed from light- 65 gauge material and the desired general planar stiffness readily achieved, the upstanding profile of the channel remote from the valve face providing the necessary locating means for a ring spring and abutment surface for a limit stop. 70 75

The provision of the annular corrugation moreover provides a radial flexibility capable of taking care of slight variations in the manufacture and wear of both the valve and its seats, and for this reason it is desirable to use only a central corrugation, avoiding upturning of the valve edges and additional stiffness in the neighborhood of the valve seats. As installed in a compressor the major convexities of the corrugations are always compassed by the higher pressure. The suction valve has thus the corrugation extending into the clearance space in the cylinder; the discharge valve is installed with the convexity of the corrugation on the receiver side of the valve. The pressure surrounding the corrugation is thus tending to reduce the angles between the adjacent valve faces from its designed 180° relation to an angle of less than 180°, forcing the lips of the valve to the seats despite the fact that the valve as a whole is materially stiffer than it would be without the corrugation. While in theory any corrugation or bead would perform the same function, it is found to be best to make a corrugation of sufficient depth to exceed the radius comprehending the difference between the radii of its inner and outer peripheries, as the maximum flexibility is so obtained. Any desired flexibility may be achieved by giving greater or less depth to the corrugation, and as an end result there is attained a valve made of light material stiff enough to permit finish of its face and possessing a degree of self-adjustment important in practice.

The form of the guard is best seen in Figs. 3 and 4, and it will be noted the guard has a lobed opening therethrough to promote flow, has a peripheral flange to act as a stop, and is dished to provide a shoulder which will cooperate in locating the spring. Obviously, due to its dishing and flanged construction it may be made of relatively light, sheet material.

While there is in this application specifically described one form which the invention may assume in practice, it will be understood that this form of the invention is shown for purposes of illustration only and that the invention may be modified and embodied in various other forms without departing from its spirit or the scope of the appended claims.

What I claim as new and desire to secure by Letters Patent is:

1. In combination, a valve comprising thin, uniformly spaced seating portions disposed in a common plane and connected by a corrugation, a valve seat having spaced seat-providing surfaces respectively engageable by said seating portions, a valve guard comprising a metallic plate having flow orifices inside its periphery and a portion projecting towards said valve seat and consti-

tuting a valve stop and engageable by said corrugation on said valve on opening movement of the latter, and a spring round in radial section and comprising a single continuous loop flexed out of a plane and engaging said valve and guard and coacting with said corrugation and with said projection. 5

2. In combination, a valve comprising thin, uniformly spaced, annular seating portions disposed in a common plane and connected by an annular corrugation, a valve seat having spaced seat-providing surfaces respectively engageable by said seating portions, a circular valve guard comprising a dished metallic plate having flow orifices inside its periphery, and, outside said orifices, a 15 peripheral rim constituting a valve stop and engageable by said corrugation on valve-opening movement, and a flexed annular spring of round stock and of a conformation flattenable substantially to unit spring-stock thickness and coacting 20 with said corrugation and with said rim.

3. In combination, annular concentric valve seats, an annular valve cooperating therewith, a transversely-bowed annular, single loop spring round in radial section, said annular valve having 25 a medial projection from its non-seating surface coacting with said spring in the positioning of the valve, and a valve guard comprising a plate having an annular projection to cooperate with said medial projection on said valve to limit valve 30 opening and ported to permit flow within its periphery.

4. In combination, a valve cage having valve seats thereon, guiding wings formed integral with said valve cage, a valve cooperating with said 35 valve seats and having uniformly spaced seating portions disposed in a common plane and connected by a corrugation, a valve guard attached to said guiding wings and having a peripheral projection which extends toward said valve and 40 is engageable by said valve corrugation on valve opening movement, a flexed annular single-loop spring round in radial cross section and formed of round spring stock of the same cross section as the radial cross section of said spring, said spring 45 engaging said valve and valve guard and positioned by said corrugation and said valve guard projection, said valve on opening movement guided by said guiding wings.

5. A valve mechanism comprising, in combination, a valve seat member, a valve cooperating therewith, a valve guard, and an annular valve spring arranged between said guard and valve comprising a single endless loop and of round radial section, and transversely bowed, said spring 55 flattenable substantially to unit spring-stock thickness when the valve is unseated.

WARREN NOBLE.
